UNITED STATES PATENT OFFICE.

GUSTAVE BURKHARDT, OF CHICAGO, ILLINOIS.

METAL LOUVER.

Application filed March 12, 1920. Serial No. 365,363.

To all whom it may concern:

Be it known that I, GUSTAVE BURKHARDT, a citizen of the United States, residing at Chicago, in the county of Cook and State of

Illinois, have invented certain new and useful Improvements in a Metal Louver, of which the following is a specification.

This invention relates to a louver constructed of metal and including not only the louver boards proper, but also the casing and the structure in which these boards or slats are set. Although particularly designed and intended as a part of a sprayer head house, the invention may be utilized wherever applicable. The principal objects of the invention are to provide a construction of this kind which is both light and strong and is so formed as to utilize a light weight sheet material and at the same time obtain a result which ordinarily could not be obtained except with a much heavier material. Another object of the invention is to construct a louver of this kind which assists in breaking up the current of air or the volume of water which strikes the louvers, thereby rendering them more effective. The invention consists in the novel construction, combination and arrangement of the parts.

In the accompanying drawing, Fig. 1 is an elevation of a sprayer head house embodying this invention; Fig. 2 is a view of a louver constructed in accordance with the principles of the invention; Fig. 3 is a section taken on the line 3—3 of Fig. 1; Fig. 4 illustrates a louver having a plurality of stiffening ribs; and Fig. 5 is a sectional view showing two adjacent louvers.

It is customary to surround sprayer heads for water cooling systems with a louver construction in which the slats are made of wood. The present invention relates to the construction of louvers of this kind of thin sheet metal, which is made possible by forming the louvers themselves in such a way that they are strengthening transversely and longitudinally, so that they have great rigidity, and still are light in weight, and will not bend or buckle when subjected to water or to high wind and rain storms.

By making the louvers with a strengthening rib or ribs which extend lengthwise thereof, the rib acts to break up and to deflect the air currents which would otherwise scatter the spray from the sprayer head. This construction also confines the sprayed water within the sprayer house so that it

will not damage the walls or roofs of adjacent property, and by allowing the free passage and circulation of air between the louvers, it causes a cooling effect on hot sprayed water.

Referring now more particularly to the drawings, the frame in which the louvers are mounted may be formed of wood or other satisfactory supports, but in its preferred construction, comprises hollow metal uprights 10, which are formed of sheet material lapped at one portion, as shown more clearly in Fig. 3.

Between the uprights 10 any number of louvers are placed, which may be placed apart any desired distance depending somewhat upon the prevailing velocity of the wind and water to which the sprayer head house is subjected, the lower extremity of one louver usually being at about the same level as the upper edge of the next lower louver, as shown more clearly in Fig. 5.

The preferred form of louver comprises a single sheet of metal of sufficient length to fit between the uprights, and this material is bent over at one edge 11 and formed with a bend 12, adjacent thereto which adapts the adjacent face 13 to be inclined to the horizontal, while the bent edge 11 is vertical. Intermediate the upper and lower edges, an offset 14 is provided by bending the material upon itself to form an overlapping shoulder or extension 15 after which the material at 16 is continued at the same inclination as the portion 13. The upper portion 17 is bent at such an angle that it is parallel to the lower edge 11, and the upper edge beyond this portion 17 is formed with a horizontal portion 18 and a downwardly bent edge 19.

In effect this construction has three longitudinal strengthening ribs, one at the lower edge, another at the upper edge, and an intermediate rib at the bend or offset. If desired, and where an extremely wide louver is to be used, this strengthening effect may be increased by correspondingly increasing the number of intermediate strengthening ribs 20, as shown in Fig. 4. These ribs act not only as a deflector for breaking up and retarding the air and water currents which pass between the louvers, but also, they act as catchers for rain and dirt which engage them from without and thereby prevent objectionable matter from passing between the louvers, and also confine the sprayed water within the sprayer house.

The ends of the louvers are formed with flaps 21 opposite the plane portions 13 and 16, and these flaps may be secured to the upstanding ribs at the center and upper edge 5 of the louver by soldering or the like, and the flaps are soldered or otherwise fastened to the uprights 10. Flaps 22 may also be left at the upper and lower edges of the louvers which can be attached at the front 10 and rear sides of the uprights 10.

With this construction it is obvious that a louver window, or a construction of this kind for protecting and enclosing sprayer heads may be made entirely of sheet metal so 15 that it is light and at the same time strong, and simple in construction. As the louvers are strengthened both transversely and longitudinally by means of the end flaps and the ribs, there is no tendency for the louvers to 20 bend or buckle, except under excessive pressure, thus obtaining this effect with lighter material which could only be produced by using a much heavier material, or by using a wooden louver, and in addition, accomplishing the other results which are described. 25

I claim:

1. A sheet metal louver slat having a longitudinal strengthening rib formed by bending the material upon itself and then 30

forming an offset in it so that the material on one side of the rib is in a different plane than that on the other side.

2. A sheet metal louver slat comprising a bent upper edge and a longitudinal 35 strengthening rib, both of which are formed to partially overhang a portion of the slat immediately below, and thus to form pockets which open outwardly.

3. The combination with hollow metallic 40 uprights, of a plurality of louver slats formed of sheet material, and each comprising longitudinal strengthening ribs, flaps at the ends for strengthening the louver slat transversely, and for attaching it to the casting, and additional flaps at the upper and lower edge of each end for attaching the louver slat to the front and rear face of the upright. 45

4. In a louver window, a plurality of 50 louver slats, each formed of sheet material and having a lower edge bent upon itself to form a strengthening rib, and the upper edge bent to overhang a portion of the louver surface and to form a strengthening rib, the 55 lower edge of one louver slat being disposed at or below the plane of the upper edge of the next lower louver slat.

GUSTAVE BURKHARDT.
